UNITED STATES PATENT OFFICE.

GEORGE W. PECK, OF ROSELLE, NEW JERSEY, EXECUTOR OF GEORGE W. BANKER, DECEASED.

CRATE FOR TILTING DEMIJOHNS.

SPECIFICATION forming part of Letters Patent No. 653,396, dated July 10, 1900.

Application filed March 1, 1900. Serial No. 7,038. (No model.)

To all whom it may concern:

Be it known that GEORGE W. BANKER, now deceased, but at the time of his death a citizen of the United States, and a resident of Keene, in the county of Essex and State of New York, prior to his death invented a new and useful Improvement in Crates for Tilting Demijohns, of which the following is a specification.

10 The invention may be more fully understood by reference to the United States Letters Patent No. 577,409, dated February 23, 1897, granted to said George W. Bunker, to which reference is made for a general description of the apparatus.

15 The improvement which forms the subject-matter of this present application consists in a novel construction of the trunnions or axes marked C in that patent, which are adapted 20 to engage with the crate which immediately surrounds the demijohn or other vessel and upon which it tilts in operation of the apparatus. These trunnions are supported in the upper ends of standards marked B B in said 25 patent, which are connected to a base-frame, and the construction is such that when the apparatus is adjusted ready for use the trunnions or axes C C engage with the crate surrounding the demijohn or other vessel at or 30 near its upper part.

Referring to the drawings hereof, Figure 1 illustrates an elevation of the invention when applied to the standards of the apparatus, which are always vertical. Fig. 2 illustrates 35 a plan view of the invention when applied to the standards of an apparatus in which the base-frame is inverted to form a complete casing or crate for the demijohn during the time of its transportation or storage. This 40 form of apparatus is shown in the pending application, Serial No. 710,278, filed March 24, 1899. Fig. 3 illustrates the parts shown in Fig. 2 when they are inverted for the purpose of forming an inclosing crate for the 45 demijohn during transportation or storage. Fig. 4 illustrates an edgewise view in section of the parts shown in Fig. 1.

A illustrates part of one of the standards. B is a recess cut therein. C is one of the trunnions. The recess B is formed so that the nut 50 D on the trunnion may not project beyond the

plane of the side of the standard, and also so that space may be afforded for the finger and thumb of the operator to catch hold of the nut to manipulate the trunnion when necessary. 55 E is a recess which is preferably formed on the opposite side of the standard, within which the head of the trunnion may enter, so that it will be flush with that side of the standard.

60 F is a trunnion-guard made, preferably, of metal and is pivoted to the standard by a pin, a small nail, or equivalent device G, so that it will freely swing under the action of gravity. It is not essential that it should be thus loose, 65 however, because it is operative and in some cases better that slight power be employed to swing or move the guard. The purpose of this guard is to prevent the trunnion from moving backwardly during the transportation or 70 movement of the crate. In Figs. 1 and 4 it is shown as pivoted at the upper side of the recess, so that it will normally fall by gravity over the nut on the trunnion, and thus confine the trunnion, because, as stated, these figures 75 show the invention as applied to the standards of non-reversible crate-supports. In Figs. 2 and 3, on the other hand, the guard is shown as pivoted at the lower side of the recess B, so that when the standards are reversed, as during 80 transportation, storage, &c., the action of gravity will tend to maintain the guards in proper position over the ends of the trunnions or nuts on them. When the trunnions are in their non-reversed position, as shown in 85 Fig. 2, then the guards under the action of gravity may fall away from the trunnions, as shown in that figure; but this is of no consequence, because when the standards of this form of the apparatus are in this position the 90 apparatus is at rest, with the weight of the crate and the demijohn resting on the trunnions, and under such circumstances they are not liable to displacement. It is only during transportation, and sometimes during 95 storage, that the trunnions are liable to shift their position, and it is more particularly to avoid this danger that the invention is intended.

100 It will be obvious to those who are familiar with this art that many departures may be made from the details shown and described

and yet the essentials of the invention be employed. There is therefore no limitation herein to such details.

What is claimed as of the invention of said 5 GEORGE W. BANKER, deceased, is—

1. In an apparatus of the class stated, the combination of a crate inclosing the vessel, a frame provided with standards, trunnions at the upper ends of the standards respectively 10 which support the crate and upon which it may tilt, trunnion-guards on the outside of the standards formed of flat pieces of metal pivoted to the standards at the upper side of the trunnions when the parts are in position 15 for transportation, for the purposes set forth.

2. In an apparatus of the class stated, the combination of a crate inclosing the vessel, a frame provided with standards, trunnions at the upper ends of the standards respectively 20 which support the crate and upon which it may tilt, trunnion-guards on the outside of the standards and resting against their outer surfaces, formed of flat pieces of metal pivoted to the standards adjacent to the trunnions, and recesses beneath the guards sufficiently large to receive the head or nut of the trunnions and to afford finger-space whereby 25 they may be manipulated, for the purposes set forth.

nion may be received, for the purposes set forth.

3. In an apparatus of the class stated, the combination of a crate inclosing the vessel, a frame provided with standards, trunnions at the upper ends of the standards respectively 30 which support the crate and upon which it may tilt, trunnion-guards on the outside of the standards and resting against their outer surfaces, formed of flat pieces of metal pivoted to the standards adjacent to the trunnions, and recesses beneath the guards sufficiently large to receive the head or nut of the trunnions and to afford finger-space whereby 35 they may be manipulated, for the purposes set forth.

Signed at New York, in the county of New York and State of New York, this 23d day of February, 1900.

GEO. W. PECK,
